UNITED STATES PATENT OFFICE

2,545,624

ROTATABLE PERFORATED TOP WITH
AGITATOR FOR POWDER CANS

John J. Mackert, Detroit, Mich.

Application October 29, 1946, Serial No. 706,381

4 Claims. (Cl. 222—242)

1

This invention relates to rotatable perforated top with agitator for powder cans, especially designed for containing tooth powder or the like, the primary object of the invention being to provide a powder can having a rotatable top provided with means for agitating the powder at the discharge opening of the top, to prevent the powder from caking at the discharge opening, and becoming so solidified that the powder will not move through the discharge opening.

An important object of the invention is to provide an agitator of this character which is so constructed and arranged that with each rotary movement of the cover to open the discharge opening of the can, the agitator will loosen and direct a quantity of powder forwardly, to the discharge opening.

Another object of the invention is to provide a cover of this character which may be manufactured at a minimum cost and without increasing the cost of the manufacture of the can cover appreciably.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawing:

Figure 1 is a plan view of a powder can equipped with the cover and cap, constructed in accordance with the invention.

Figure 2 is a bottom plan view thereof, a portion of the agitator blade having been broken away, illustrating the construction of the pivot of the rotary cap.

Figure 3 is a sectional view taken on line 3—3 of Figure 1.

Figure 4 is a sectional view taken on line 4—4 of Figure 1.

Referring to the drawing in detail, the reference character 5 indicates a tooth powder can which is formed with a raised spout 6 which is closed with the exception of the discharge opening 7 and the central opening 8, through which the strap 9 of the inner rotary section 10 extends. The inner rotary section 10 is formed with an annular flange 11 which is cut away as at 12, the cut away portion 12 extending an appreciable distance into the main portion of the inner rotary section 10, providing a discharge opening, adapted to register with the discharge opening of the spout 6

for permitting powder to pass from the can through the discharge opening.

Formed integral with the inner rotary section 10, is an agitating blade 13 which is substantially triangular in shape, the blade being wide to cut under the powder which is delivered within the spout, for discharge through the discharge opening of the can.

As clearly shown by Figure 3 of the drawing, 10 this agitating blade 13 extends towards the inner rotary section, the free edge of the blade being disposed at a point adjacent to the discharge opening 7, the blade being inclined with respect to the annular flange 11.

15 Cooperating with the inner rotary section 10, is an operating disc 14 which is formed with a finger 15 that fits under the strap 9 which is struck from the rotary section 10 and bent upwardly out of its plane, where it is extended 20 through the opening 8 in a position to receive the finger 15 securing the operating disc 14 and the inner rotary section 10, together, so that rotary movement of the operating disc 14, will rotate the section 10 to align the opening of the 25 inner rotary section 10 with the discharge opening 7.

The segmental flange 16 is formed on the operating disc, and this flange is formed with a roughened surface to permit easy operation of 30 the operating disc 14, when the finger of the person using the can, is moved over the flange 16.

From the foregoing, it will be seen that due to the construction shown and described, with each movement of the operating disc 14 or cover, to 35 align the openings of the rotary section and the spouts, the agitating blade 13 will not only agitate the powder which collects within the spout, maintaining the powder loose, but will at the same time act to direct a quantity of the powder towards the registering openings where it may pass from the can.

What is claimed is:

1. In a powder can, a spout having a discharge opening, a closure for the spout, said closure comprising an inner rotary section having an opening adapted to register with the discharge opening of the spout, and a substantially triangular inclined agitator blade connected at one of its ends with the inner rotary section the opposite 45 end of the blade being free and adapted to pick up and direct the powder towards the discharge opening as the inner section is rotated, and means for rotating the inner rotary section and blade.
2. In a powder can, a spout having a discharge 50 opening, an inner rotary member mounted with-

in the spout and having a discharge opening adapted to register with the opening of the spout permitting material to pass from the can, an operating disc mounted exteriorly of the spout and having connection with the inner rotary member whereby rotary movement of the operating disc operates the inner rotary member, and an agitating blade inclined with respect to the rotary member mounted on the inner rotary member at one end of the blade, the opposite 10 end of the blade being free and adapted to cut into the material within the can and agitate material adjacent to the discharge opening.

3. In a powder can, a spout having a closed outer end formed with a discharge opening and having a central opening, an inner rotary member mounted within the spout, a strap formed on the inner rotary member and being extended through the central opening of the spout, an operating disc mounted on the spout, a finger extending from the operating disc and adapted to be positioned within the strap of the inner rotary member, securing the operating disc and inner rotary member together, whereby movement of the operating disc operates the inner rotary member, and a blade carried by the inner rotary member, said blade being inclined and adapted to direct powder towards the discharge opening, when the operating disc and inner rotary member are rotated.

4. In a powder can, a spout having a discharge opening, an inner rotary member mounted with-

in the spout and having an opening adapted to register with the discharge opening of the spout, permitting material to discharge from the can, an operating disc mounted on the spout and having a segmental flange extending downwardly therefrom, providing a finger piece, means for connecting the inner rotary member and operating disc whereby movement of the operating disc rotates the inner rotary member, and an inclined agitating blade secured to the inner rotary member at one end of the blade and operating adjacent to the discharge opening the opposite end of the blade being free and inclined towards the rotary member adapted to pick up material and direct material to the discharge opening as the inner rotary member is rotated.
